UNITED STATES PATENT OFFICE.

CHARLES E. THOMPSON, OF LANSINGBURG, NEW YORK.

DESIGN FOR A BOX.

SPECIFICATION forming part of Design No. 18,747, dated November 20, 1888.

Application filed August 30, 1888. Serial No. 284,902. Term of patent 14 years.

To all whom it may concern:

Be it known that I, CHARLES E. THOMPSON, a citizen of the United States, residing at the village of Lansingburg, county of Rensselaer, 5 and State of New York, have invented and produced a new and original Design for Boxes, of which the following is a specification, reference being had to the accompanying drawings, forming part thereof.

10 Figures 1 and 2 of the drawings are side elevations of my newly-designed box, the one representing a slight modification of the other. Fig. 3 is a top plan view of same. Fig. 4 is a central vertical section of the box shown in Fig. 2.

15 The leading feature of my design consists of an annular funnel or saucer shaped flange flaring outward from the open end of a box, having rounded or curved sides and a rounded 20 bottom.

I have shown in Fig. 2 a box having a cylindrical body, A, closed at the lower end, as by bottom C, and provided at its open end with

the annular funnel-shaped flange B, flaring outward from the edge of the opening. 25

Without departing from my general design, the flange may be concaved or saucer-shaped, as shown in Fig. 1, and the lower or bottom edges of the box rounded or beveled, as shown at D D'.

30 What I claim as new, and desire to secure by Letters Patent, is—

The design for a box herein shown and described, the same consisting of a body part having curved or rounded sides closed at one 35 end by a rounded bottom and open at the other end, and an annular flange projecting outwardly and upwardly from the rounded sides at the open end of the body part.

In testimony whereof I have hereunto set my hand this 13th day of August, 1888.

CHAS. E. THOMPSON.
